HEART MASSAGING DEVICE

James J. Lally, 800 W. 52nd Terrace, Kansas City, Mo.

Filed Jan. 7, 1964, Ser. No. 78,102

Term of patent 14 years

(Cl. D83—1)

FIG. 1 is a top plan view of a heart massaging device, showing my new design;

FIG. 2 is a side elevational view thereof;

FIG. 3 is an elevational view of one end; and

FIG. 4 is a fragmentary elevational view of the opposite end of a heart massaging device.

I claim:

The ornamental design for a heart massaging device, as shown.
